R. D. SMITH,
RECIPROCATIVE ACTUATING MECHANISM,
APPLICATION FILED AUG. 14, 1916. RENEWED NOV. 17, 1919.
1,350,574.

Patented Aug. 24, 1920.

UNITED STATES PATENT OFFICE.

RAYMOND D. SMITH, OF MILTON, MASSACHUSETTS, ASSIGNOR TO TREMONT PRODUCTS COMPANY, OF BOSTON, MASSACHUSETTS, A CORPORATION OF MASSACHUSETTS.

RECIPROCATIVE ACTUATING MECHANISM.

1,350,574.

Specification of Letters Patent. Patented Aug. 24, 1920.

Application filed August 14, 1916, Serial No. 114,782. Renewed November 17, 1919. Serial No. 338,533.

To all whom it may concern:

Be it known that I, RAYMOND D. SMITH, a citizen of the United States, residing at Milton, in the county of Suffolk and State 5 of Massachusetts, have invented certain new and useful Improvements in Reciprocative Actuating Mechanism, of which the following is a specification.

My invention relates to actuating means 10 for a rotative, reciprocating control device or element (such as, for example, a rotary valve member) wherein by reciprocative rotation, through a limited number of degrees, the device (or valve member) effects appropriate control of some ultimate means, (e. g. 15 opens or closes valve ports) as desired. More particularly the present invention concerns an improvement in the type of partially automatic gas valve actuating mechanism disclosed in my co-pending application, Serial No. 110,950, filed July 24, 1916. In such apparatus it is sometimes desired to have a free movement of the gas port control device in one direction, but to have the 20 movement in the other direction, or a part thereof, effected automatically;—and for that purpose means are provided whereby the device is maintained by a stop or detent against full movement in said other direction 25 but tension is established to cause such movement automatically after a desired delay interval, the stop or detent being then automatically retracted.

It is convenient to combine the port control device and the automatic actuating means with single acting or unitary control means, whereby movement of the device in both directions is primarily secured or governed.

40 In such an arrangement, I have found it advantageous, for certain purposes, to provide a further developed means of actuation and control whereby, through the same manual, or other, controlling instrumentalities, 45 the port control device, after having been put under such tension, and under the control of said automatic means for desired movement, may be given the desired movement immediately and without awaiting the 50 time interval requisite for the securing of such movement by said automatic means.

For the sake of simplicity in manual operation, I preferably so associate the said further means of actuation and control with 55 the said unitary control means that a mere

repetition of the manual act initially adapted to place the said device under control of said automatic actuating means, and of said detent, may release such device from restraint by such detent, thereby causing immediate and undelayed movement. 60

My invention, therefore, provides means in such a described combination for accomplishing the described purpose.

The particular embodiment of my invention, herein chosen for illustrative purposes only, is adapted for use with an illuminating gas burner, and although the scope of my invention is by no means confined to such use, it will be obvious that when so used a specific object thereof is to provide, in conventional form, simple, and preferably reciprocating, manual control means for the valve governing the supply of gas to such burner, whereby said valve may be opened 70 by actuation of said control means in one direction, and put under control of automatic means for causing a delayed closure thereof, by actuation of said control means in the reverse direction; and whereby a 75 repetition of the last said actuation shall cause immediate closure of said valve.

Other details and objects of my invention will appear from the drawings, description, and claims hereof. 80

In the drawings: Figure 1 is a side view, in elevation, of a structurally combined open flame gas burner and controlling valve therefor, together with mechanism for actuating said valve, in which mechanism is 90 embodied one form of my present invention, the mechanism casing being shown broken away; Fig. 2 is a front view of the device shown in Fig. 1 looking at the right of the latter figure with the casing omitted, the 95 parts being positioned so as to permit normal operation of the burner; Fig. 3 is an enlarged plan view of the valve actuating mechanism taken partly in section on the horizontal planes 3—3 in Fig. 6; Fig. 4 100 shows, on a larger scale, the mechanism of Fig. 2 at the beginning of its movement adapted to cause closure of the valve and thereby extinguishment of the light; Fig. 5 shows the position of parts at the extreme 105 of the movement begun in Fig. 4; Fig. 6 shows the position of parts after being released by the manual or other actuating means which caused the movement of parts from their positions as shown in Fig. 2 to 110

the position in Fig. 5; Fig. 7 shows the position of parts brought about by repetition of the actuation represented in Figs. 4 and 5; Fig. 8 is an enlarged partial section, 5 taken on the vertical plane 8—8 in Fig. 1, showing the arrangement of operative valve ports and their relation during normal operation of the illuminating burner; Fig. 9 is a section similar to Fig. 8 showing the relation of ports after actuation of the extinguishing means but before automatic closure of the valve; Fig. 10 shows the relation of ports after the light has been extinguished.

15 Throughout the drawings and in the following description, similar parts are designated by like numerals.

In Fig. 1 the flame of the main burner appears at 10. The usual burner stem 11 is shown mounted upon a valve block 12, which block contains the usual tapered valve plug 15 lying horizontally transverse of the upright main gas passage 18, which plug by rotation is adapted in the usual manner 20 to govern the supply of gas to the burner. The valve plug 15 has a stem 30 extending axially from its smaller end, and carrying a loose spacing collar 34, a loose irregularly shaped, double-ended lever 35 and a double-extended dog member 36, said dog member being made fast to the end of the valve stem by a key screw 42.

A coiled spring 38 connects the lever 35 and the dog member 36 in such a way as normally to maintain a radially projecting spur portion 24 of the former in engagement with a rearwardly extending arm 37 of the latter, such engagement establishing the normal rotative relation of these parts shown in Figs. 35 2, 4 and 7.

40 At one end of the lever 35 is shown pivoted a bell-crank latch 66 suitably limited in its movement and yieldingly held in a position by the spring 73 such that the latch may engage with a stationary projection 78 and thereby lock the lever 35 in the position shown in Figs. 5, 6 and 7 when this lever is made to assume such position.

On the opposite side of the fulcrum the 50 lever 35 carries a compound lever arrangement consisting of an auxiliary control arm 26 pivoted to the lever 35 at 27, extending exterior of the mechanism casing, and carrying pivoted thereto a short pawl finger 28 55 swingable about its pivot 29, into and out of a position in which such pawl finger has a function by its movement with the arm 26 to be referred to hereafter. The pawl finger 28 is normally, but yieldingly, maintained in its operative position by the spring 39 and by a stop projection 40 carried by the pawl finger, while the auxiliary control arm, itself, is normally and yieldingly maintained in a position relative to the lever 35 60 such as is shown in Figs. 2, 4 and 5 by the

spring 41 and by its spur portion 51, which latter is adapted to engage with a forwardly projecting stop 43 on the lever 35. The forwardly bent extremity 44 of the lever 35 serves as another stop for the auxiliary control arm 26, by engagement with a curved notch 49 in the latter, and acts operatively upon a cam portion 50 of the pawl finger 28 to render the latter inoperative to perform its heretofore mentioned function 70 when said bent extremity of the control lever 35 is fully engaged with the notch 49.

The dog member 36 carries at the extremity of a radial extension 45, thereof, a yoked latch member 46 pivoted thereto and arranged to yield in only a counter-clockwise direction in Fig. 7, against the tension of the small coiled spring 48.

Lying normally in the path of movement 85 of the latch member 46 is a spur-shaped detent 52, carried fast to the inner surface of a curved, bi-metallic thermostat 53, which latter is securely anchored at one end to a projecting abutment 54, extending forwardly from the upright, circular supporting plate 90 31. This supporting plate is mounted rigidly on the valve block 12 and carries a stationary roller abutment 61 internally adjacent to the free end of the thermostat and is adapted to reinforce the latter against 95 excessive flexural yielding when said thermostat is subjected to the thrust imparted by pressure of the latch member 46 upon the spur detent 52 as shown in Figs. 5 and 6.

The thermostat is arranged to open, or 100 straighten, upon being thermally energized, which movement it will be plain, retracts the detent 52 radially outwardly and away from the path of movement of the latch member 46.

105 Clamped to the mounted end of the thermostat and extending rearwardly from the same, is a mono-metallic, heat conducting member 56 which terminates as shown in Figs. 1 and 2 in a hollow, hooded, or inverted cup-shaped, portion 57, adjacent to the burner stem 11 and external of the mechanism housing. This terminal hood has a small opening 58 at its top and is entirely open at the bottom.

110 Directly over and slightly below this terminal portion of the heat conducting member 56, is the fuel outlet of a small auxiliary heating member 21, structurally integral with the valve block 12 and of Bunsen 115 burner construction, to which the supply of gas may be regulated by the screw 23. As shown in Fig. 9, the valve plug 15 has an additional port 19 adapted to register, in suitable rotative position of the former, 120 with a corresponding port 20 in the valve block, which latter port leads to the burner 21. Gas may thus be delivered to the burner 21 under control of the valve plug 15, whereupon such gas will rise and ignite 125 130

from the heat of the main flame 10, subsequently burning at the mouth of the burner 21 with a hot, blue, flame from which heat may be transmitted to the thermostat by the heat conducting member 56. A casing 33, is provided to house the mechanism and convenient manual control is provided by the cords 65 and 68.

Having thus described the construction of a particular and useful application of my present invention, I shall now explain the operation thereof, assuming the parts to be positioned as shown in Figs. 1 and 2, where, the valve ports are related as shown in Fig. 8, and where it will be clear that the main burner is lighted and adapted to operate for an indefinite period of time, the auxiliary burner receiving no fuel and therefore being inactive. When it be desired to cause extinguishment of the light by closing the valve, cord 65 is pulled downwardly, causing a movement of parts to the positions shown in Fig. 4, and further, to the position of certain parts indicated by broken lines in this figure, when, as shown in Fig. 5, the movement of latch member 46 and thereby of the dog member 36 and valve plug 15 is intercepted by the spur detent 52. After such interception, however, further pull upon the cord 65 effects a movement of the lever 35 and its carried parts, against tension of the spring 38, to the position shown in Fig. 5, where the lever 35 is shown locked under such tension by means of the latch 66 as heretofore explained. It should be noted, that during this latter movement of parts, although the end 59 of the pawl finger 28 designedly projects into axial alinement with the free end 60 of the thermostat 53, this pawl finger has not engaged the end of the thermostat, having been swung radially inwardly, by the cam action of the bent end 44 of the lever 35, said end being fully engaged with the notch 44 in the auxiliary control arm 26 as shown in Fig. 5.

Upon release of the cord 65, the control arm 26 is returned to its position as shown in Fig. 6 by the spring 41, during which movement the end 59 of the pawl finger may wipe by the end 60 of the thermostat. The valve ports are now related as shown in Fig. 9 and gas is thereby delivered to the auxiliary heating burner 21 which ignites from the flame 10 as heretofore explained and acts to heat the thermostat. Upon being thus heated, the thermostat straightens or bends generally outwardly assuming after a certain time interval the position indicated by broken lines in Fig. 6, wherein the detent 52, has been retracted and the dog member 36 being thus released has been rotatively impelled by the spring 38 to the position shown in Fig. 7, causing thereby a relation of valve ports such as shown in

Fig. 10 where all gas supply to both the main and auxiliary burners has been stopped, and such burners consequently extinguished.

If however it be desired to accomplish such extinguishment without awaiting the time interval requisite to heat the thermostat and cause such action automatically, cord 65 may again be pulled. This second actuation, since the pawl finger is now in its normal position, uninfluenced by the end 44 of lever 35, causes pawl finger 28 to engage with the end of the thermostat and by pressure thereupon, to produce a flexure of said thermostat substantially equivalent to its thermally caused flexure, whereby, it will be clear, that immediate closure of the valve and extinguishment of the light will be had.

When it be desired to again open the valve to supply fuel to the burner, cord 68 is pulled, which first will move the latch 66 to its broken line position in Fig. 6, thus unlocking the lever 35 which latter may then be restored, together with all of its carried parts, to the original position as in Fig. 2, whereupon the main burner may be lighted and remain in operation indefinitely or until subsequent actuation of cord 65.

It will be evident to those skilled in the art, that the particular embodiment of my invention which I have herein described is but one of many possible applications of the principles and spirit of my true invention, such means of accomplishing such multiple functions by simple control means being advantageous to diverse mechanisms entirely foreign to the control of gas flow.

Without therefore, limiting the scope of my invention to the precise embodiment herein disclosed, what I claim as my invention is:

1. Actuating mechanism for operating a tension rotated device embodying, in combination with said device; a spring-connected actuator member arranged by movement to a relatively advanced position to tension said device for relative follow-up movement; an automatically governed detent normally operative to prevent said follow-up movement of said device; a releasable detent for holding said member in its said advanced position when said device is so tensioned; and separately actuatable means for tripping said automatically governed detent,—said means being operably related to said member and arranged to be rendered inoperative thereby except when said member is held in its said advanced position.

2. Actuating mechanism for operating a tension-rotated device, embodying in combination with said device; a pivoted actuator member having a resilient connection to said device and adapted to be locked in a

position to tension said device for rotative movement; a movable detent normally arranged and positioned to prevent said movement of said device thereby to hold the latter rotatively separated from said member when the member is moved to its said position; and tripping mechanism mounted for movement relative to said member and adapted upon separate actuation to free said device from said detent, said mechanism being operatively related to said member thereby to be maintained inoperative to trip said detent except when said member is locked in its said position.

3. Actuating mechanism for operating a tension-rotated device, embodying in combination with said device; an oscillatory actuator pivoted concentrically with said device and having a resilient connection thereto and abutting engagement therewith, whereby said member and said device are normally maintained in definite rotative relation but rotatably separable in one direction of relative oscillation; a latch to lock said member in an extreme position thereby to tension said device for follow-up movement relative to said member; a movable detent normally arranged and positioned to prevent said follow-up movement of said device when said member is moved to its said position; and tripping mechanism mounted for movement relative to said member and adapted for separate actuation to free said device from said detent; said tripping mechanism being constructed and arranged to be maintained inoperative to trip said detent except when said member is locked in its said position.

4. Actuating means for a rotative device adapted for reciprocative movement, embodying, in combination with said device; a member concentrically pivoted with said device; a resilient, normally tensioned connection between said device and member, the said device and member being further so cooperatively formed that relative rotative movement therebetween is positively limited;—means partly carried by said member, to releasably hold said member proximate to an extreme rotative position; a movable detent and arranged and positioned normally to intercept and hold said device rotatively separated from said member when said connected device and member are moved in a direction toward said position; and means carried by said member and adapted upon actuation to release said device from said detent; said last mentioned means being constructed and arranged to be maintained inoperative until said member has been locked in said extreme position.

5. In combination with actuating means for a rotatable device mounted for limited movement, said device having controlling instrumentalities therefor, including a mov-

able detent normally arranged and positioned to prevent said movement of said device; a pivoted actuator member having resilient connection to said device whereby the latter may be tensioned for rotative movement against the restraining action of said detent; and a tripping device for said detent, pivotally mounted on said member and adapted for limited movement relative thereto,—said tripping device extending radially from said member to serve as an actuating extension for the latter.

6. In combination with actuating means for a rotatable device adapted for limited, reciprocative movement, said device having controlling instrumentalities therefor associated with a movable detent normally arranged and positioned to arrest the movement of said device in one direction; a pivoted, reciprocating member having resilient connection to said device whereby said device may be tensioned for movement in said direction, against the action of said detent; and a spring actuated pawl arrangement carried by said member and comprising an arm pivoted thereto and extending therefrom to serve as an actuating medium therefor, together with a tripping pawl, carried by said arm, and normally adapted by movement therewith to release said device from restraint by said detent, but so formed and positioned as to be operatively engaged by a portion of said pivoted member, during actuation of the latter by said arm, and thereby to be displaced from a position operative to cause such release of said device.

7. Actuating means for a rotative, reciprocative, device having associated controlling instrumentalities adapted to permit free movement of the device in one direction, and including a detent normally positioned to intercept said device in the reverse direction, said actuating means embodying, in combination; a double-ended lever pivoted concentrically with said rotative device, having positive engagement therewith to effect said free movement of the device, and having resilient connection therewith for effecting movement of said device in said reverse direction, and to tension said device for further movement when the latter is intercepted by said detent; a latch arranged to lock said pivoted lever automatically when said device is so tensioned, said latch being carried by said pivoted member and forming an actuating extension therefor; and an arm pivoted to said lever and also forming an actuating extension therefor, said arm carrying pivoted thereto a spring actuated pawl, the said arm and the said pawl being so cooperatively formed and associated and so operatively positioned on said pivoted member that movement of said arm relative to said pivoted member when the latter is locked by said latch shall be operative, by

means of said pawl, to release said device from restraint by said detent.

8. Actuating means for a rotative valve stem having operatively associated therewith an automatic valve turning means including a controlling thermostat, and embodying in combination; a pivoted member adapted for limited, reciprocal movement, said member being resiliently connected to the valve stem, and arranged to move said stem positively in one direction only, and provided with oppositely disposed radial arms fixed thereto; a latch device partially carried by one of said arms and operatively associated therewith to automatically and releasably lock said member near one extreme of its travel; means fixed to said valve stem and arranged to engage with a detent operably related to said thermostat, thereby to intercept the valve stem in its non-positive movement caused by movement of said member toward its said locked position; and means carried by the other arm of said member and operatively related to said thermostat 25 in the said locked position of said member, to effect release of the valve stem from restraint by said detent, upon actuation of said last mentioned means.

9. Actuating means for a rotative valve stem having operatively associated therewith automatic valve turning means including a controlling thermostat, and embodying in combination; a member concentrically pivoted with said valve stem and adapted for limited, reciprocal movement, said member being resiliently connected to the valve stem, and arranged to move said stem positively in one direction only, and provided with oppositely disposed, radial arms 40 fixed thereto; a latch lever pivoted to one of said arms and extending therefrom to automatically and releasably lock said member near one extreme of its travel and also to serve as an actuating medium for said member; means fixed to said valve stem and arranged to engage with a detent operably related to said thermostat, thereby to intercept the valve stem in its non-positive movement caused by movement of said member to the latter's locked position; and an auxiliary lever pivoted to the other radial arm of said member and extending therefrom to serve as an actuating medium therefor; together with a tripping pawl, carried 55 by said auxiliary arm and normally adapted, in said locked position of the said member and by movement with said auxiliary arm, to deflect said thermostat, and thereby to release said valve stem from restraint by said detent; said pawl being so formed and positioned as to be operatively engaged by a portion of said pivoted member, during actuation of the latter by said auxiliary arm, and thereby to be displaced from a position

operative to cause such release of said valve 65 stem.

10. Actuating means for a rotative gas valve stem having operatively associated therewith automatic valve turning means including a controlling thermostat, and embodying in combination; a member concentrically pivoted with said valve stem and adapted for limited, reciprocal movement, said member being resiliently connected to the valve stem, and arranged to move said stem positively in one direction only, and provided with oppositely disposed, radial arms fixed thereto; a latch lever pivoted to one of said arms and extending therefrom to automatically and releasably 70 lock said member near one extreme of its travel, and also to serve as an actuating medium for said member; means fixed to said valve stem and arranged to engage with a detent operably related to said thermostat, 75 thereby to intercept the valve stem in its non-positive movement caused by movement of said member toward its said locked position; and an auxiliary arm pivoted to the other radial arm of said member and also 80 forming an actuating extension therefor, said auxiliary arm carrying pivoted thereto a spring actuated pawl, the said auxiliary arm and the said pawl being so cooperatively formed and associated and so operatively positioned on said pivoted member that movement of said auxiliary arm relative to said member, when the latter is locked by said latch lever, shall be operative to deflect the thermostat by means of said pawl, 85 thereby to release said valve stem from restraint by said detent.

11. Actuating means for a rotative gas valve stem having operatively associated therewith automatic valve turning means including a controlling thermostat, and embodying in combination; a member concentrically pivoted with said valve stem and adapted for limited, reciprocal movement, said member being resiliently connected to 100 the valve stem, and arranged to move said stem positively in one direction only, and being provided with oppositely disposed, radial arms fixed thereto, a latch lever pivoted to one of said arms and extending therefrom to automatically and releasably lock 105 said member near one extreme of its travel, and also to serve as an actuating medium for said member; means fixed to said valve stem and arranged to engage with a detent operably related to said thermostat, thereby to intercept the valve stem in its non-positive movement caused by movement of said member toward its said locked position; and an auxiliary arm pivoted to the other arm of 110 said member and also forming an actuating extension therefor, said auxiliary arm being so formed and so positioned on said 115

120

- member that movement of said auxiliary arm about its pivot when said member is in its locked position shall be operative to deflect the detent-engaged thermostat, thereby 5 to cause a release to said valve stem from restraint by said detent, and so that common movement of said auxiliary arm with said member about the axis of the latter shall be inoperative to effect such release.
- 10 12. In combination; a rotatable device; an oscillatory, spring returned actuating extension therefor and mounted for movement relative to said device; a spring to tension said device for automatic movement, and 15 arranged to be energized therefor by a stroke of said extension in one direction; a detent normally operative to prevent said movement of said device; and mechanism to trip said detent for freeing said device, said 20 mechanism being arranged co-operatively with said extension to be rendered inoperative thereby until a repetition of a part of said extension stroke in said direction.
13. A gas valve embodying an oscillatory 25 gas port control member; an oscillatory actuator element mounted to swing with, and positively to impel, said member in one direction of its oscillation, and further arranged for swinging displacement relative 30 thereto in the opposite direction of oscillation; a spring connection between said element and said member whereby said relative displacement of said element tensions said member for follow-up movement from a 35 port-opening to a port-closing position; a

detent arranged normally to prevent said follow-up movement of said member when said element is displaced therefrom; means to hold said element so displaced; and normally inactive, slow-acting instrumentalities 40 arranged to be operatively energized when said element is so displaced, and thereby rendered active to free said member from said detent after a substantial interval of time; together with separately actuatable 45 mechanism for directly tripping said detent, said mechanism being arranged to be held inoperative until said member and said element are relatively displaced.

14. In gas valve control apparatus of the 50 type wherein a rotatable port control member is tensioned for port-closing rotative movement by the locking of a spring-connected actuator therefor in a certain position, and wherein an automatically governed 55 detent is normally arranged to prevent said port-closing movement, the combination with said element and with said detent; of a separately actuatable tripping device for freeing said member from said detent, said 60 device being operably related to said element and thereby rendered inoperative until after said element is locked in its said tensioning position.

Signed in Boston, Massachusetts, this 12th 65 day of August, 1916.
